UNITED STATES PATENT OFFICE.

PHILIP E. MOORE, OF McHENRY, MISSISSIPPI.

COMBINED TIE AND JOINT.

1,300,290.

Specification of Letters Patent. Patented Apr. 15, 1919.

Application filed January 10, 1918. Serial No. 211,155.

To all whom it may concern:

Be it known that I, PHILIP E. MOORE, residing at McHenry, Mississippi, have invented certain new and useful Improvements in Combined Ties and Joints, of which the following is a specification, reference being had therein to the accompanying drawings, forming a part hereof.

This invention comprises a combined rail-way tie and joint. It is contemplated among its objects to produce a metal tie which will adapt itself to a large range of uses; which will consist of few parts so assembled that they will receive and retain a rail securely and positively to the elimination of uneven joints and spreading; which can be assembled and disassembled with a minimum of fastening or securing elements; which will lend itself readily to the use of various fillers, sound-deadening compositions, ballast and the like, and which will, in a word, provide a very practical device for this purpose.

Other objects and advantages will be in part apparent, and in part developed more fully in the description which follows.

Drawings are included which illustrate an embodiment of the invention, the following views being shown:

30 Figure 1, is a view in perspective illustrating a single, and a double tie construction embodying my invention, and a rail joint in conjunction therewith;

Fig. 2, is a view in top plan of a double form of tie and joint;

Fig. 3, is a view in bottom plan thereof;

Fig. 4, is a view in longitudinal section of a tie and joint of the type shown in Figs. 2 and 3;

40 Fig. 5, is a view in top plan of one of the components of this form; and

Fig. 6 is a view in longitudinal section of a single tie and rail securing means.

In these drawings 1 designates a double tie and 2 a single tie embodying my invention. Each has a body portion 3, and side flanges 4 to constitute an integral support or saddle which may be filled with concrete, sound-deadening compositions, ballast and

50 the like after the tie has been assembled and secured in place in connection with a rail.

For this purpose each tie, or form of tie is provided on the body portion thereof, with openings 5, an edge of which is struck up to

55 form a lip or flange 6 adapted to receive and retain a flange of a rail 7. These lugs

are at one end of the openings 5, and preferably arranged in pairs on the body of the tie, one at each extremity thereof in the single form and two or more sets in the double 60 etc.

Adapted to coöperate with these lugs in retaining the rail in place on the tie, there is provided a locking member having a body portion 8, in which there are openings 9, upon corresponding, oppositely disposed edges of which openings there are struck up lugs or retainers 10. This locking member is adapted to be placed on the under side of the tie in a position which will permit the 70 lugs 10 to pass through the openings 5 in the body portion of the tie and coöperate with the lugs 6 thereon to engage and retain the flange of the rail 7.

Means are also provided for securing the 75 members in locked position, and as here shown comprise openings 11 in both the tie and locking members, said openings being adapted to register when the members are in locked position, and be secured in this relation by a bolt or the like 12.

It is contemplated, in the present invention, to provide a fish plate or rail joint in combination with the tie structure just described, and as here shown such joint comprises extended portions 6' of the lugs 6, and extended portions 10' of the lugs 10, which extensions are shaped to engage the web portion of the rail. These extended portions are provided with openings which are adapted to register with the bolt-holes in the ends of the rails, and be secured thereto suitably as by the usual bolts 13.

As an additional locking means for the members, and for the purpose also, of preventing lateral movement between the members, the body portion may be provided with straps or the like 14, which extend across the openings 5 in the body portion and are depressed centrally so as to lie in the plane of the locking member 8 when it is in position as shown in Fig. 6. By this means an edge of the opening 9 in the member 8 engages an edge of the strap 14, and forms a positive lock against the transverse movement of 100 either part, when so assembled.

While I have disclosed my invention in the embodiment herein illustrated, it will be understood that the general principles of its application are herein shown, and I do not 110 desire to be confined to this particular method of putting them into operation. It

is contemplated to use the members without the flanges 4, particularly in bridge and the like constructions, or in any other location where it might be desirable to secure the 5 tie to a wooden or other separate base. Many other changes may be made in the general construction and arrangement of the parts without departing from the scope of the invention as set forth in the claims.

10. What I claim is:—

1. A combined railway tie and joint comprising coacting locking members each provided with an opening and with a lug at one edge of the opening; one of said members 15 being adapted to be associated with the other member, the lug on one member passing through the opening in the other member and juxtaposed to the lug on the other member to receive and to retain a rail flange; and 20 automatic means for locking the members when so assembled.

2. A combined railway tie and joint comprising coacting locking members each provided with an opening and with a lug at

one edge of the opening; one of the members being adapted to be associated with the other member, the lug on one member passing through the opening in the other member and juxtaposed thereto to receive and retain between said lugs, a rail flange; and an upstanding member carried by a lug adapted to engage and be secured to a web of the rail. 25 30

3. In combination with rails arranged end to end, a combined tie and joint comprising coacting members each provided with an opening and with a lug at one edge of said opening; said members being associated, a lug on one member passing through an opening in the other member and retaining a flange of a rail therebetween; automatic 40 means for locking the members when so assembled; and an upstanding member disposed on a lug and secured to the web of the rails to constitute a connection therefor.

In testimony whereof I hereunto affix my 45 signature.

PHILIP E. MOORE.
